H. E. SHREEVE

VACUUM TUBE

Filed Feb. 20, 1918

by

55 Herbert E. Shreeve.
J. E. Roberts Atty.

UNITED STATES PATENT OFFICE.

HERBERT E. SHREEVE, OF MILLBURN, NEW JERSEY, ASSIGNOR TO WESTERN ELECTRIC COMPANY, INCORPORATED, OF NEW YORK, N. Y., A CORPORATION OF NEW YORK.

VACUUM TUBE.

Application filed February 20, 1918. Serial No. 218,254.

To all whom it may concern:

Be it known that I, HERBERT E. SHREEVE, a citizen of the United States, residing at Millburn, in the county of Essex and State 5 of New Jersey, have invented certain new and useful Improvements in Vacuum Tubes, of which the following is a full, clear, concise, and exact description.

This invention relates to improvements in 10 vacuum tubes, and more particularly it relates to improvements in shells for audions whereby each audion is provided with terminal connections which may be readily made or severed without disturbing the fixed 15 wiring of the circuits allied therewith.

As is well known in the art, it has been found convenient to surround the base of the glass bulb of a vacuum tube by a tubular shell or collar having a base-piece on 20 which are mounted terminal connections for the leading-in wires to the various electrodes of the tube; and these terminal connections are usually arranged to cooperate with spring clips or other forms of contacts in 25 a base or socket adapted to receive the collar.

One object of this invention is to provide a new form of shell for vacuum tubes of a type which possesses many novel advantages 30 over those heretofore employed, such as ease of construction and attachment to a tube for the various functions it performs.

In the preferred form of this invention, the hollow cylindrical form of the shell is 35 made from thin sheet material of the proper dimensions with its ends suitably welded or fastened together. Near one end of the cylinder, and projecting radially inward, is provided a suitable ledge or shoulder on 40 which may rest an insulation base-piece to which are attached contact posts or other suitable terminal connections for the vacuum tube electrodes. The base-piece on being put in position may be held firmly in place 45 against the shoulder by crimping the lower edges of the walls of the cylinder over the base-piece. When such a shell is applied to surround the base of a vacuum tube, the upper edges of the shell, on account of its 50 thinness, may be made to fit snugly to the walls of the tube. In order that the leading-in conductors may be readily attached to the external contact post, the insulation base-piece is preferably made in a more or less

web-like form with large openings, and the 55 contact posts may each be provided with clips electrically connected with the post and projecting over the openings. As it is usual to secure the collar to the bulb by some suitable sealing material, this material may, 60 after the lead wires have been fastened to the post, be poured through the openings in the base-piece so as to fill up the space between the bulb and the collar. With such a structure, the collar is snugly and firmly 65 secured to the bulb.

These and other novel elements of the structure will be better understood from the following detailed description taken in connection with the accompanying drawings, in 70 which Fig. 3 represents one modification of this invention and Figs. 1 and 2 are details thereof. Fig. 6 is a modification of Fig. 3 in which an additional contact post is provided. Figs. 4 and 5 are details of Fig. 75 6. Fig. 7 shows this invention mounted on the neck of a vacuum tube. Fig. 8 shows the form of this invention shown in Fig. 3 in connection with a socket with which it is adapted to cooperate. Fig. 9 is a cross-sectional view taken along the section line 9—9 of Fig. 8.

First referred to in Fig. 3, this illustrates a shell composed of a collar 12 and an insulation base 13. The details of the collar 85 are shown in Fig. 2, while Fig. 1 illustrates the details of the insulation base. As shown in Fig. 2, the collar is composed of a sheet of material which has been shaped in the form of a cylinder with its ends welded or otherwise suitably fastened together at the points 90 14. Near one end of the cylinder is an outwardly facing groove which forms, on the inner wall, a ridge 15, which, as shown in Fig. 3, serves as a shoulder against which 95 the insulation base may rest. A projection 17 on the inner wall is also provided whose function will be explained later. 18 is a pin that is adapted to fit into a slot in a vacuum tube socket, as will be hereinafter 100 described. If it is desired to apply any patent marking to the vacuum tube, this may be readily stamped on the shell and owing to the difficulty of stamping cylindrical objects, it has been found preferable 105 to do the stamping while the sheet material of the shell is flat.

As shown in Fig. 1, the insulation base

is of a web-like form having three contact posts or electrodes 20, 21 and 22, suitably mounted thereon. Each of these posts is in electrical contact with a clip 25 having 5 a tapered portion which projects beyond the edges of the insulation and to which wiring connection may be readily made. One arm of the web has a notch 27 therein, which is adapted to engage with the projection 17 10 of the collar, whereby the position of the contact posts is determined with respect to the pin 18 when the web is put into position against the shoulder 15, as shown in Fig. 3. After the web has been inserted in its proper 15 position, the edges of the cylinder may be crimped over at a plurality of points 30 to hold the web in place.

In Fig. 6 is shown a shell having a collar 12 (see Fig. 5) which is of similar structure 20 to the collar of Fig. 2, but the web 33, as shown in Fig. 4, has four arms, each having a contact post 34 provided with a clip mounted thereon. The web is fastened in the collar as has been described above.

25 Fig. 7 shows the shell after it has been placed around the neck of a vacuum tube 40. The shell may be secured firmly to the neck by some suitable sealing material which may be poured through the arms of the web 30 and over the web until it is flush with the edges of the collar. Four leading-in conductors 41, 42, 43, 44 to the electrodes of the tube are shown, each conductor being suitably fastened to one of the contact posts 34.

35 In Fig. 8 the sealing material between the neck of the bulb and the collar has been omitted in order to show more plainly the manner of connecting the leading-in conductors to the contact posts. The tube 40 is 40 an audion of the ordinary type having three electrodes therein, a filament 46, a grid 47 and an anode 48. Such a tube has four leading-in conductors 49, two of the leads being for the filament, one for the grid and one for 45 the anode. If the shell surrounding the neck of the tube has only three contact posts, three of these leads may be connected to the three posts, while the fourth lead may be soldered or otherwise attached to the collar 50 itself, thereby employing the collar as a terminal connection. One form of a socket with which such a shell may be engaged is shown in this figure to be composed of a base-piece 51 and a socket member 52 integral therewith. Attached to the base-piece is a plurality of contact pieces 53, 54, 55 and 56, the first three of which end in the 55 spring contacts 57, 58 and 59 which are disposed under the socket opening in such a manner that each makes contact with one of the contact posts of the shell when the shell is inserted in the socket with the pin 18 in the slot 62. The fourth contact piece 56 (see Fig. 9) is electrically connected to the 60 metallic socket member 52, and consequently

connected to the collar 12 so that said contact piece forms an external terminal connection for the leading-in wire which is connected to the collar.

Fig. 9 illustrates how the contact piece 70 56 may be electrically connected to the base-piece 51 by a counter-sunk bolt 64 which is in electrical contact with the base-piece 51 and the contact piece 56.

The shell illustrated in Fig. 6, which has 75 four contact posts, is adapted to readily cooperate with a socket somewhat similar to that of Fig. 8 comprising an additional spring contact instead of the connection through the collar of the shell and the base-piece of the socket. Such a socket with four spring contacts is illustrated and described in my Patent No. 1,325,865, December 23, 1919, vacuum tube sockets.

This invention is not limited to the two 80 forms described above for, as is evident to one skilled in the art, various modifications may be made therein without departing in any wise from the spirit of this invention as defined in the appended claims.

What is claimed is:

1. A shell for the neck of a vacuum tube, comprising a collar, a web of insulation material partially closing one end of said collar, terminal connections mounted on said web for said tube, said shell being mounted on said neck, and sealing material surrounding said web.

2. A shell for the neck of a vacuum tube, comprising a collar, a web of insulation material partially closing one end of said collar, terminal connections mounted on said web for said tube, and means comprising a sealing material for surrounding said web and holding said collar to said tube.

3. The combination of a socket having terminals, a vacuum tube comprising electrodes having different characteristics adapting them for connection to different circuits, a collar for the neck of said tube, an insulating element carrying electrical terminals for said electrodes, certain of said socket terminals being adapted to be simultaneously connected to corresponding ones of said tube terminals, means for determining the relative angular positions of said collar and said socket with respect to the longitudinal axis of said collar, and means for so fixing the relative angular positions of said carrying means and said collar with respect to said axis as to insure that only corresponding ones of said socket terminals and said tube terminals will be engaged.

4. A shell for the neck of a vacuum tube having electrodes, comprising a collar, a shoulder projecting from the inner surface of said collar, a web of insulation material comprising a central portion with radial arms resting on said shoulder, terminal connections for said electrodes comprising a

- contact post mounted on each of a plurality of said arms, and a sealing material surrounding said web for securing said collar to said tube.
5. A shell for the neck of a vacuum tube having electrodes, comprising a collar, a shoulder projecting from the inner surface of said collar, a web of insulation material supported by said shoulder, terminal connections mounted on said web for said electrodes, and means for determining the position of said web on said shoulder.
6. The combination of a socket having terminals, a shell for the neck of a vacuum tube, said shell comprising a collar, a web of insulation material, terminal connections mounted on said web for said tube, and means for insuring that certain ones of said terminals on said web make contact with certain ones, respectively, of said terminals of said socket, said last-mentioned means comprising means for fixing the position of said shell with respect to said socket, and means for fixing the position of said web with respect to said shell.
7. The combination of a socket having terminals, a shell for the neck of a vacuum tube, said shell comprising a collar, a web of insulation material, terminal connections mounted on said web for said tube, coupling means for determining the position of said shell in said socket, and a cooperating notch and projection for fixing the position of said web with respect to said shell, whereby the terminals on said web make contact in a predetermined manner with the terminals of said socket.
8. A shell for the neck of a vacuum tube having electrodes, comprising a collar, a shoulder projecting from the inner surface of said collar, a web of insulation material supported by said shoulder, terminal connections projecting through said web for said electrodes, and means for determining the position of said web on said shoulder.
9. A shell for a neck of a vacuum tube having electrodes, comprising a collar, a plate of insulating material adapted to occupy a certain angular position in the outer end of said collar with respect to the axis of said collar perpendicular to the plane of said plate, terminal connections carried by said plate for said electrodes, and means whereby in fitting said plate in said collar the said certain angular position for said plate with respect to said collar may be readily fixed.
10. A shell for the neck of a vacuum tube having electrodes, comprising a collar, a shoulder projecting from the inner surface of said collar, a web of insulation material supported by said shoulder and having a notch in its edge, a projection on said collar adjacent said shoulder, said projection adapted to register with said notch to hold the web in a definite position in the shell.
11. The combination of a socket having terminals, a shell for the neck of a vacuum tube, said shell comprising a collar, a web of insulation material having a notch in its edge, terminal connections mounted on said web for said tube, means for determining the position of said shell with respect to said socket, and means for fixing the position of said web with respect to said shell comprising an inner projection on said collar adapted to register with said notch, whereby the terminals on said web may contact in a predetermined manner with the terminals of said socket.
12. A shell for the neck of a vacuum tube having electrodes, comprising a collar, a plate of insulating material fitted in the outer end of said collar, and terminal connections carried by said plate for said electrodes, said plate and said collar being so formed as to determine the angular position of said plate in said collar with respect to the axis of said collar perpendicular to the plane of said plate.

In witness whereof, I hereunto subscribe my name this 21st day of January, A. D. 1918.

HERBERT E. SHREEVE.
